RADIO RECEIVING SET

John Edwin Petersen, Oak Park, Ill.

Application December 19, 1935, Serial No. 55,167

13 Claims. (Cl. 250—14)

The invention relates to radio receiving sets and has for its general object the provision of a set arranged in a novel compact manner in an upstanding casing or support of such form and size that it is adapted for use as a decorative article of house-furnishing such as a lamp pedestal or base.

More particularly, it is an object to provide a radio set enclosed within a generally cylindrical upstanding casing having a rotatable control member adjacent the lower end of the casing arranged concentrically therewith and thereby providing a harmonious inconspicuous relation to the appearance of the casing.

It is also an object to provide a radio set of the foregoing character in which a loud speaker is located in the upper part of the casing with a grille or apertured cover thereover constituting the top of the casing and supporting the shade bracket of a lamp.

Other objects and advantages will become apparent from the following description taken in connection with the accompanying drawing, in which:

Figure 1 is an elevational view on a reduced scale of a combined lamp and radio receiving set embodying the features of the invention.

Fig. 2 is a vertical sectional view of the pedestal of the device shown in Fig. 1.

Fig. 3 is a horizontal section taken on the line 3—3 of Fig. 2.

Fig. 4 is a horizontal section taken on the line 4—4 of Fig. 2.

Fig. 5 is a fragmentary horizontal section taken on the line 5—5 of Fig. 2.

Fig. 6 is a fragmentary horizontal section taken on the line 6—6 of Fig. 2.

The preferred embodiment of the invention comprises generally an upstanding casing enclosing radio apparatus and mounted in spaced relation above a base. The radio apparatus includes, among other parts, a loud speaker mounted in the top of the casing and a rotatably adjustable element mounted in the lower part thereof. To adjust said element, a rotatable control member is located in the space between the casing and the base and conforms in appearance thereto. The control element is so fashioned as to permit the casing to be rigidly supported by the base.

In the present instance, the casing and base constitute the pedestal of a lamp, and to support the electric sockets and shade of the lamp, a cap is provided for the upper end of the casing, which is apertured to permit egress of the sound from

the loud speaker. Extending from the cap is a bracket for the sockets and shade.

As shown in the drawing, the casing is in the form of a vertically extending cylindrical sleeve 10 of material having a decorative appearance, which may be varied to suit different tastes in the matter of decoration. The sleeve 10 is carried by an internal frame structure, indicated generally at 11, and is positioned in spaced relation above a base 12. The latter is preferably hollow 10 and carries means for supporting the casing comprising a pair of threaded members 13 holding the casing in suitably spaced relation by spacers 14.

Within the casing is the radio apparatus including an adjustable element which, in the present instance, is the rotatable element of a variable condenser 15 mounted in the lower part of the casing. The rotatable element has a shaft 16 extending below the casing.

To adjust said element, a control member is mounted in the space provided by the spacers 14 between the casing and the base 12, and in its preferred form is a disk-shaped member 20 attached to the shaft 16 as by bushing 21 and lock 25 nut 22. The control member 20 is rotated to adjust the condenser 15 and is of sufficient diameter to extend at least to the periphery of the casing 10 so that it may be manually operated. In the form illustrated, the member 20 has a 30 beveled periphery 23 extending beyond the periphery of the casing and having suitable graduations 24 thereon to cooperate with a fixed point or arrow 25 on the base 12. In appearance, the beveled periphery 23 harmonizes with the casing 10 and base 12 so that it becomes inconspicuous as to its function.

Since the casing 10 is fixedly supported by the threaded members 13 and the control member 20 rotates, the latter is constructed to permit of 40 such rotation with the threaded members 13 extending through the control member. To this end, the control member 20 is provided with a pair of arcuate slots 26 through which the threaded supporting members 13 extend. The 45 range of adjustment for the condenser 15 is preferably approximately 180°, so that the slots 26 are given such length, and the supporting members are placed at different radial distances from the axis of rotation to permit the slots to be 50 given such length without opening into each other.

The radio apparatus receives power through an electrical cord 27 entering the hollow base 12 through an aperture 28. To conduct the cord 27

into the casing one of the threaded supporting members 13 (see Fig. 2) is tubular in form, thus providing a conduit for the cord which does not interfere with the adjustment of the control member 20. A wire for attachment to an aerial may also pass out through tubular supporting member 13 along with the cord 27.

The internal frame structure 11 preferably provides the support for the radio apparatus, so that the sleeve 10 merely serves as an enclosure and as a decorative exterior, the sleeve being carried by the frame structure. Thus, the frame structure 11 comprises, in the present instance, a pair of strips 30 preferably made of sheet metal 15 with their ends bent at right angles to provide attachment lugs. Connecting the strips 30 are transverse parts placed at whatever heights as are desired to support the various pieces of radio apparatus. In the preferred embodiment, a 20 transverse part comprising a strip or plate 31 connects the bottom ends of the vertical strips 30. If desired, one of the threaded supporting members 13 may be used to attach one of the vertical strips 30 to the transverse plate 31 at one 25 end and a bolt and nut 32 used to attach the other end of the transverse plate 31 to the other vertical strip 30.

The preferred embodiment also includes a transverse plate 33, in the form of a disk, intermediate the upper and lower ends of the strips 30, to support tube sockets 34 of the desired number and tubes 35. To simplify manufacture, each vertical strip 30 is made of two parts in end-to-end relation and secured together by bolts 36 which 35 also secured the transverse plate 33 at that height. A condenser 37 as well as resistors and wire connections for the tubes may be carried on the lower face of the plate 33.

The upper end of the casing is utilized for the 40 loud speaker mounted concentrically with the casing and comprising a pot 40, a cone 41 and a cone support 42. Preferably the pot 40 is supported by a rod 43 threaded into the transverse plate 33 while the periphery of the cone support 42 is carried on the upper ends of the vertical frame strips 30 and is secured thereto as by bolts 44. To provide rigidity, a reinforcing ring 45 is placed over the periphery of the cone 41 and is secured by the bolts 44. Chokes 49 may be carried 45 by the cone support 42. To close the upper end of the casing, a cap 46 of suitable external appearance and configuration and provided with apertures to permit the egress of sound is also secured on the upper end of the casing by the 50 bolts 44.

The sleeve 10 of the casing is preferably secured in place at both ends by rings 47 clamped in place by the frame bolts and preferably having flanges 48 telescoping over the respective ends of 60 the sleeve 10. The upper end of the sleeve 10 may have a plurality of apertures 57 to provide ventilation for the casing.

As mentioned above, the casing and base 12 are of such form that they are adapted for use 65 as a decorative article of house-furnishing such as a lamp pedestal or base. To this end a bracket comprising a pipe 50 is supported by the cap 46 and constitutes a support for suitable lamp sockets 51 and for a shade 52. For wiring, the electrical cord 27 supplying current to the 70 radio set may be tapped inside of the casing as by branch wires 52, and the latter carried up within the casing to a notch 53 in the reinforcing ring 45 and thence into the pipe 50.

75 A combined switch and rheostat 54, constitut-

ing part of the radio apparatus, may also be mounted in the casing, preferably in the lower part thereof, and supported by the ring 47, with its adjusting shaft 55 extending through the wall of the casing to receive an external knob 56.

5 In operation, electrical current is carried to the radio set by the cord 27 and is controlled by the combined switch and rheostat 54. To adjust the condenser 15, the control member 20 may be rotated by placing the fingers on the external 10 beveled surface 23 thereof. The arcuate slots 26 in the control member permit rotation thereof without interference by the fixed casing supporting members 13.

The radio apparatus is all compactly enclosed 15 in a casing of relatively small size and of such form and appearance that is remarkably adapted to serve as the base or pedestal of a lamp. The external portion of the control member 20 harmonizes with the adjoining casing and base 20 12 so that it is relatively inconspicuous, while the cap 46 serves to permit egress of sound from the loud speaker and has an appearance artistically conforming to the casing in its function as a lamp pedestal.

25

I claim as my invention:

1. A radio receiving set comprising, in combination, a base, an upstanding casing, supporting means for supporting said casing in spaced relation above the base, radio apparatus enclosed within said casing including a variable element, and a control member for said element comprising a disk located in the space between said casing and base and operatively connected to said element, said control member being arcuately 35 apertured to permit said supporting means to extend therethrough and thereby permit rotation of said control member.

2. A radio receiving set comprising, in combination, a base, a casing disposed about a vertical 40 axis, a pair of supporting members for supporting said casing in spaced relation above the base, radio apparatus enclosed within said casing including a rotatably adjustable element mounted for rotation concentrically with said casing, and a control member for rotating said element comprising a disk located in the space between said casing and base concentrically with said casing and secured to said element, said control member having a pair of arcuate slots through which 50 said supporting members extend to permit rotation of said control member.

3. A radio receiving set comprising, in combination, a base, a cylindrical casing positioned with its axis vertical, a pair of supporting members for supporting said casing in spaced relation above the base, radio apparatus enclosed within said casing including a rotatably adjustable element mounted for rotation concentrically with said casing, and a control member for rotating 60 said element comprising a disk located in the space between said casing and base concentrically with said casing and secured to said element, said control member having a pair of arcuate slots to permit said supporting members to pass 65 therethrough, said supporting members being at different radial distances from the axis of rotation with the slots correspondingly arranged whereby each of said slots may be at least 180° in length.

70

4. A radio receiving set comprising, in combination, a base, a casing disposed about a vertical axis, means for supporting said casing in spaced relation above the base, radio apparatus enclosed within said casing including a 75

5 rotatably adjustable element, and a control member for said element comprising a disk located in the space between said casing and base and operatively connected to said element, said control member being arcuately slotted to permit said supporting means to extend therethrough and having sufficient diameter to extend at least to the periphery of said casing whereby it may be manually adjusted and harmoniously blends into

10 the external appearance of the base and casing.

5. A radio receiving set comprising, in combination, a base, a casing, a pair of laterally spaced supporting members for supporting said casing in spaced relation above the base, radio apparatus enclosed within said casing including

15 a rotatably adjustable element, a rotatable control member connected to said element within said casing and located in the space between said casing and base, said control member having

20 apertures for said supporting members to pass therethrough, one of said supporting members being tubular, and an electrical wire connection for the radio apparatus extending from the base through said tubular supporting member and into

25 the casing.

6. A radio receiving set comprising, in combination, a base, a frame structure, means for supporting said frame structure in spaced relation above the base, radio apparatus carried by

30 said frame structure including a rotatably adjustable element, a rotatable control member for said element concentric with said base and located between said base and frame structure, and a casing enclosing said frame structure and carried thereby.

35 7. A radio receiving set comprising, in combination, a base, a frame structure comprising vertically extending parts connected at their lower ends by a transverse part, means for sup-

40 porting said transverse part in spaced relation above said base, radio apparatus carried by said frame structure including a rotatably adjustable element mounted on said transverse part, a rotatable control member for said element located between said transverse part and said base, and a casing concentric with said control member enclosing said frame structure and carried there-

45 by.

50 8. A radio receiving set comprising, in combination, a base, a casing disposed about a vertical axis, means for supporting said casing spaced above said base, radio apparatus mounted within said casing including a condenser mounted in the lower part of the casing and having a rotatably adjustable element, and a rotatable control member concentric with said casing and located between said casing and base, said control member being operatively connected to said element.

55 9. A radio receiving set comprising, in combination, a base, a frame structure comprising

vertically extending parts and a pair of transverse parts, one intermediate the ends of the vertically extending parts and the other at the lower ends thereof, radio apparatus carried by said frame structure including an adjustable condenser mounted on the lower transverse part, tubes carried on the intermediate transverse part, and a conical loud speaker suspended from the upper ends of said vertically extending parts, means for supporting said lower transverse part spaced above said base, a rotatable control member operatively connected to said condenser and located between said base and said lower transverse part, and a casing enclosing said frame structure and radio apparatus.

5

10

15

10. A radio receiving set comprising, in combination, a base, a generally round casing positioned above said base with its axis vertical, means for supporting said casing spaced above said base, radio apparatus mounted within said casing including an adjustable condenser located in the lower part of the casing, means for adjusting said condenser comprising a disk rotatably mounted in the space between said base and said casing, and a loud speaker mounted in the upper end of said casing and having an upwardly facing cone concentric with the casing.

15 11. A radio receiving set comprising, in combination, a base, a generally round casing positioned above said base with its axis vertical, means carried by the base for supporting said casing spaced above said base, radio apparatus mounted within said casing including a rotatably adjustable condenser located in the lower part of the casing, and a disk concentric with said casing and located in the space between said base and said casing, said disk being suspended from said condenser and being rotatable for adjusting the condenser.

20 12. A radio receiving set comprising, in combination, a base, a frame structure including a transverse part supported in spaced relation above said base, a casing enclosing said frame structure, radio apparatus carried by said frame structure within the casing including a condenser mounted on said transverse part and having a rotatably adjustable element mounted on a vertical axis, and a rotatable control disk located in the space between said transverse part and the base and carried by said adjustable ele-

35

40

45

50

13. A radio receiving set comprising, in combination, a base, a generally round casing supported by and above said base, radio apparatus within said casing including a rotatably adjustable element, and a rotatable control member for said element located below said casing and concentric therewith, said control member extending adjacent the periphery of the casing whereby it may be readily manipulated.
